FOLDABLE CARDBOARD BOTTLE CARRIER

Eli N. Castle, South Orange, N. J.

Application January 10, 1950, Serial No. 137,813

5 Claims. (Cl. 229—28)

1

This invention relates to a bottle carrier and it is one object of the invention to provide a carrier which is formed from a single blank of cardboard, or other suitable sheet material, and is of such construction that the blank may be folded and form a carrier divided into bottle receiving pockets by partitions extending longitudinally and transversely of the carrier.

Another object of the invention is to provide a carrier wherein the longitudinally extending partition is formed of sections which are detachably connected with each other and thus held in position for forming the longitudinal partition and also holding end walls forming portions of the blank in place across ends of the bottom of the carrier.

Another object of the invention is to provide a carrier having a bottom which is foldable transversely along a longitudinally extending fold line, the carrier also having end walls and transverse partitions which are flexible so that when end sections of the longitudinal partition are released from each other, the carrier may be collapsed to a flattened condition in which its side walls are disposed in close face to face relation to each other.

Another object of the invention is to so form the carrier that while it may be disposed in either a folded or extended position it will be firmly held in the extended position and its parts prevented from moving out of proper relation to each other.

With these and other objects in view, the invention consists of an improved construction and arrangement of parts, one practical embodiment of the invention being illustrated in the accompanying drawings wherein:

Figure 1 is a view looking down upon the blank from which the improved bottle carrier is formed;

Figure 2 is a perspective view of the carrier when partially formed;

Figure 3 is a top plan view of the carrier;

Figure 4 is a sectional view, taken longitudinally through the carrier, along the line 4—4 of Figure 3;

Figure 5 is a transverse sectional view, taken along the line 5—5 of Figure 3; and

Figure 6 is a view showing a corner portion of the carrier in perspective with portions in section.

This improved bottle carrier is formed from the blank shown in Figure 1, and referring to this figure, it will be seen that the blank has a center portion 1 and side strips 2 and 3, the side strips having end portions free from and

2

projecting beyond ends of the center portion 1 and the strip 3 having extensions 4 disposed along their inner sides and spaced from ends of the center section 1. The center section is creased longitudinally midway its width to form a fold line 5 and along opposite side edges of the center section are fold lines 6. The center section 1 forms the bottom 7 of the carrier and the side strips 2 and 3 are foldable upwardly along the lines 6 to form side walls 8 which are attached to the bottom along opposite sides thereof.

After the side strips have been bent upwardly to form the side walls 8, the free end portions 15 of the strips are folded inwardly towards each other to form sections 9 of end walls 10 of the carrier and inner ends of the free end portions of the strips are each formed with a plurality of transversely spaced parallel creases 11 so that the end walls will be connected with the side walls by arcuate corner portions 12 which follow the curvature of the rounded corners of the bottom 7.

After forming the end walls, the ends of the strips are bent inwardly along the fold lines 13 to form inwardly extending portions which form transverse partitions 14 for the carrier. These partitions are each formed with a plurality of transversely spaced creases 15 so that their inner end portions may be disposed parallel and in close face to face relation to each other and the companion partitions then curved away from each other and extend transversely of the carrier towards the side walls 8. Outer ends of the transverse partitions are bent along fold lines 16 to form lips 17 and these lips are glued or otherwise secured against inner faces of the side walls. Since the partitions are creased to form the lines 15, they may be moved from an extended position to a folded position in which they extend longitudinally of the carrier and are disposed flat against the corner forming portions of the side strips. The partition-forming portions of the side strip 2 are cut along arcuate lines 18 to form tongues 19 and these tongues are glued or otherwise securely fastened against inner faces of the end wall forming portions of the strip 3 so that the two end wall sections 9 will be firmly held in meeting relation to each other.

Before the end portions of the side strips are bent to form the end wall sections 9 and the transverse partitions 14, the flaps 4 of the strip 3 are bent along the fold lines 20 which extend between inner ends of the flaps and inner ends

of slits 21 extending from outer ends of panels 4 to the inner ones of the transversely extending creases 15, and when these flaps are bent along the fold lines, they will be disposed longitudinally of the carrier and have their outer end portions disposed between the parallel end portions of the transverse partitions. The inner parallel end portions of the transverse partitions are glued against opposite side faces of outer ends of the flaps, and it should be noted that inner ends of the flaps are bent along fold lines 22 to form lips or tongues 23 which are disposed flat against side faces of the flaps and serve as reinforcements for ends of a longitudinal partition 24 which has end sections 25 formed by the two flaps 4.

Tongues 26 are cut from the flaps to provide the free inner ends of the partition sections 25. The tongues of the two partition sections extend in directions opposite to each other and when the partition sections 25 are grasped by their free inner ends, the tongues may be passed through openings 27 formed by the tongues and the tongues then disposed in overlapping and interlocked engagement with each other and thus cause the two sections 25 to form a partition extending the full length of the carrier. When the tongues are released from each other, the bottom 7 may be folded along the line 5 and the transverse partitions will be flattened and the side walls moved to a position in close proximity to each other. The carrier will thus be folded and collapsed to a flat mass and a number of the collapsed carriers stacked upon a shelf in a store or wrapped for shipment by a manufacturer. The slots 28 register and form openings through which portions of a handle may be engaged and thus allow the carrier to be lifted and conveniently carried from one place to another.

From the foregoing description of the construction of my improved device, the operation thereof and the method of assembly will be readily understood, and it will be seen that I have provided a comparatively simple, inexpensive and efficient means for carrying out the various objects of the invention.

While I have particularly described the elements best adapted to perform the functions set forth, it is apparent that various changes in form, proportion and in the minor details of construction may be resorted to, without departing from the spirit, or sacrificing, any of the principles of the invention.

Having thus described the invention, what is claimed is:

1. A carrier comprising a bottom, side walls united with opposite side edges of said bottom and having end portions free from the bottom and extending longitudinally therefrom and bent towards each other across ends of the bottom and meeting midway the width of the bottom and forming end walls of the carrier, the said free portions of the walls being bent inwardly at their intersection with each other and forming partitions bent transversely of the bottom and secured at their ends to inner faces of the side walls, the said partitions having tongues cut therefrom and secured against portions forming the end walls, and the partition-forming portions at one side having extensions along their inner sides partially severed therefrom and bent upwardly and forming end portions of a longitudinal partition, the said side extensions having outer ends secured between ends of the transverse partitions and having inner ends cut to form tongues detachably

engageable with each other to releasably secure the said side extensions in overlapped partition-forming engagement with each other, and said bottom being foldable transversely along a fold line midway its width to reduce the carrier to a folded position disposing the transverse partitions and the rear wall forming partitions longitudinally of the carrier and in engagement with each other.

2. A collapsible carrier formed from a unitary blank of sheet material having a central portion forming a bottom for the carrier, strips extending longitudinally of the bottom and integrally united therewith along opposite sides thereof and having free end portions extending beyond ends of the bottom, said strips being bent upwardly along opposite sides of the bottom and forming side walls of the carrier and having their free end portions bent towards each other and forming end walls of the carrier and then bent inwardly and forming extensions secured to the side walls and forming transverse partitions, the end wall forming portions of one strip having tongues cut from them and secured against inner faces of the end wall forming portions of the other strip, one strip having its end wall forming portions formed with transverse extensions extending along their inner sides and partially severed therefrom and constituting flaps bent upwardly and secured between attached ends of the transverse portions and forming end sections of a longitudinal partition having inner ends cut to form tongues detachably connected in overlapping engagement with each other and holding the longitudinal partition in place and thereby maintaining the end wall portions in place across ends of the bottom.

3. A carrier formed of sheet material and comprising a bottom, side walls extending upwardly along opposite side edges of said bottom and having free end portions folded towards each other and secured and forming end walls for the carrier and then bent inwardly against each other and having portions bent towards the side walls and secured at their outer ends to the side walls and forming transverse partitions in the carrier, flaps along side edges of the partition forming portions of one side wall partially severed therefrom and bent upwardly and secured between the said partition-forming portions and having free inner end portions and carrying tongues interlocked and detachably holding the flaps in engagement with each other and thereby forming a longitudinal partition in the carrier; and said bottom having a longitudinal fold line midway its width adapting the carrier to be flattened when the flaps are released from each other.

4. A carrier comprising a bottom, side walls projecting upwardly along sides of said bottom, end walls formed of sections free from the bottom and extending towards each other from ends of said side walls and integral therewith, and having extensions bent inwardly and extending into end portions of the carrier and secured at their ends to the side walls and forming transverse partitions in the carrier, the extension forming one end wall portion at each end of the carrier being provided with a tongue secured to the companion end wall portion and securing the companion end wall portions to each other, and flaps integral with but partially severed from one extension at each end of the carrier and disposed longitudinally of the carrier between companion extensions, said flaps

having inner ends detachably connected with each other and thereby forming a longitudinal partition in the carrier.

5. A carrier comprising a bottom, side walls projecting upwardly along sides of said bottom, end walls formed of sections extending towards each other from ends of said side walls and integral therewith, and having extensions extending into end portions of the carrier and toward the side walls secured at their ends to the side walls and forming transverse partitions in the carrier, the extension forming one end wall portion at each end of the carrier being provided with a tongue secured to the companion end wall portion and securing the companion end wall portions to each other, and flaps integral with but partially severed from one extension at each end of the carrier and disposed longitudinally of the carrier between companion extensions and having outer end por-

tions folded inwardly and forming reinforcing strips, said flaps having inner end portions formed with tongues interlocked with each other and releasably holding the flaps in engagement with each other and thereby forming a longitudinal partition in the carrier, and said strips and portions of the extensions at opposite sides thereof being formed with handle-receiving openings.
